UNITED STATES PATENT OFFICE.

WALTER J. SIX, OF INDIANAPOLIS, INDIANA.

PISTON.

Application filed June 20, 1925. Serial No. 38,517.

To all whom it may concern:

Be it known that I, WALTER J. SIX, a citizen of the United States, and a resident of Indianapolis, county of Marion, and State of Indiana, have invented a certain new and useful Piston; and I do hereby declare that the following is a full, clear, and exact description thereof, reference being had to the accompanying drawings, in which like numerals refer to like parts.

This invention pertains to pistons particularly adapted for use in internal combustion engines.

The object of the invention is to provide a piston of the usual character but differing from pistons of ordinary structure in that the skirt portion thereof is formed separately from the head and rigidly secured thereto so that it may be made from sheet metal provided with separate and spaced bearing faces. The sheet metal is such that the bearing faces may engage the cylinder wall under spring tension so as to conform thereto and eliminate slap of the piston while at the same time avoiding any danger of seizing and scoring. This piston structure enables pistons to be installed in re-ground cylinders as well as others without the necessity of obtaining an exact fit.

The full nature of the invention will be understood from the accompanying drawings and the following description and claims:

Fig. 1 is a central vertical section through a portion of the cylinder wall showing the piston mounted therein in elevation. Fig. 2 is the same as Fig. 1 showing the bearing side of the piston. Fig. 3 is a central vertical section down through the bearing surfaces of the skirt of the piston showing the same in expanded position. Fig. 4 is a plan view looking at the top of the piston from the under side thereof, when in expanded position.

In the drawings there is shown a cylinder 10 in which the piston is mounted so as to reciprocate therein in the usual manner. The piston shown herein comprises a cast metal head 11, having the usual flanged periphery 12 provided with a plurality of peripheral grooves 13 adapted to receive the usual piston rings 14. Cast integral with the head, are the wrist pin bosses 15, extending downwardly from the opposite sides of the head or the flange portion 12 thereof,

and connected thereto by the web portion 16.

Whereas, heretofore, it has been the custom to cast the head, skirt and wrist pin bosses integral, in this instance, only the head with its depending flange and the wrist pin bosses are cast in one piece, and the skirt is formed separately therefrom of sheet metal, after which it is rigidly secured to the head as will be described.

The skirt is herein shown as a sheet metal stamping wherein there is formed the oppositely disposed bearing portions 17 spaced from each other, said bearing surfaces conforming substantially to the curvature of the head. Toward the top thereof, the metal is reduced or cut away to provide the oppositely disposed reduced neck portions 18. Said reduced neck portions terminate in a connecting strip 19 between the bearing portions 17, so bent as to extend upwardly within the flange portion of the head and fit snugly against the under surface of the head, between the wrist pin bosses as shown in Fig. 3. This connecting strip 19 is rigidly secured to the under surface of the head by the bolts 20, or it may be rigidly welded or secured thereto by any other suitable means.

The sheet metal, of which the skirt is formed, has a certain springlike characteristic, such that the skirt portions 17 may be compressed toward each other under spring tension. Thus, before the piston is installed, the skirt portions 17 are flared outwardly or expanded to a slight degree as shown in Fig. 3. Upon insertion in the cylinder, they will be compressed toward each other and bear against the wall of the cylinder under spring tension as shown in Fig. 1. By reason of the reduced neck portion 18, as well as the free portion of the connecting band 19, the spring movement will be taken up at a point adjacent the head. As the skirt may readily be compressed, there can be no seizing or scoring of the piston or cylinder, and as there is a constant outward pressure exerted by the skirt against the wall of the cylinder, a close fit will be assured, thus preventing any slapping. The heat acquired by the piston, and particularly the head thereof can have no material effect upon the expansion or contracting of the skirt for the above reasons. Thus, the expansion and contraction of the metal used is of no consequence.

The skirt portion may be formed of any suitable metal such as bronze, aluminum or any metallic compositions, and by reason of its character, and the large area of the skirt which is cut away, the piston will be relatively light as compared with other structures. Furthermore it is adaptable to accommodate itself to slightly varying sizes of cylinders, thus enabling its installation to be simplified as well as permitting its ready adaptability to reground cylinders. Thus, the characteristics of this piston have many advantages which may readily occur to those familiar with the art.

15 The invention claimed is:

1. A piston comprising a cast metal head provided with double wrist pin bosses cast integral with the under top surface thereof, and a skirt formed of sheet metal separately from said head, said skirt being rigidly secured to the under top surface of said head intermediate said bosses.
2. A piston comprising a cast metal head provided with depending wrist pin bosses cast integral with the under top surface thereof, and a skirt formed of sheet metal separately from said head, having oppositely

disposed bearing surfaces spaced from each other, said skirt being secured to the under top surface of said head intermediate said bosses.

3. A piston having a cast metal head, downwardly extending wrist pin bosses cast integral therewith, and a skirt formed from sheet metal independently of said head having oppositely disposed bearing surfaces separated and spaced from each other, a connecting band between the bearing surfaces of said skirt and means for rigidly securing said skirt to the under side of said head.

4. A piston comprising a cast metal head formed with downwardly extending wrist pin bosses cast integral with said head, a skirt of sheet metal, formed separately from said head, and having oppositely disposed bearing surfaces separated and spaced from each other, and a connecting strip connecting the upper portions of said bearing surfaces with each other and rigidly secured to the under side of said head intermediate the bosses.

In witness whereof, I have hereunto affixed my signature.

WALTER J. SIX.
